(57) **CLAIM**

The ornamental design for a sleeve, as shown and described.

DESCRIPTION

FIG. 1 is a front elevational view of a sleeve, showing my new design;

FIG. 2 is a top plan rear elevational view thereof;

FIG. 3 is a bottom plan view thereof;

FIG. 4 is a right side elevational view thereof, shown with an unclaimed wearer; and,

FIG. 5 is a left side elevational view thereof, shown with an unclaimed wearer.

The sleeve shirt design is characterized by an animal jaw on each sleeve.

The broken lines shown in the drawings are for illustrative purposes only and form no part of the claimed design.
